2,403,316

RADIOACTIVE APPARATUS

Clarence W. Wallhausen, Morristown, N. J., assignor to United States Radium Corporation, New York, N. Y., a corporation of Delaware

Application July 14, 1943, Serial No. 494,616

5 Claims. (Cl. 250—72)

1

This invention is concerned with self-luminous indicators such as clock dials, electrical instrument dials, and the like, and provides an improved apparatus having a much longer life than those available heretofore.

It has been customary to produce self-luminous instrument dials by painting the dials with a paint comprising a phosphor, i. e. a phosphorescent material such as zinc sulphide, and a radioactive material such as a radium salt which gives off rays that bombard the phosphor and cause it to glow. Dials so constructed are used in a variety of instruments and have recently found wider application in airplane instrument dials, especially in air-craft adapted for night flying.

It has been found that self-luminous indicator dials fashioned as described above have relatively short useful life, even though the proportion of radioactive material employed is high. This is believed to be due to the fact that the bombardment of the phosphor (e. g. zinc sulphide) by radium results in deterioration of the phosphor (e. g. sulphide crystal) and the eventual loss of luminosity. Whatever be the explanation, I have found that the useful life of self-luminous indicator dials, and the like, can be increased many fold if means are provided for interrupting the bombardment of the phosphor by rays, etc., from the radioactive material, except during times when observations are being made. By employing a face member, such as an indicator dial, having thereon a marker comprising a phosphorescent coating material that is non-radioactive but is capable of being activated by alpha rays, an activator member coated with a non-luminous radioactive material capable of emitting alpha rays and spaced from but operatively associated with the face member, and means for interrupting the passage of alpha rays from the activating member to the marker, I am able to increase the useful life of the phosphorescent coating material many times. A simple form of apparatus of my invention comprises a transparent slide, for example a plate of glass which carries markers, for example numbers painted thereon with non-radioactive but responsive zinc sulphide paint. Back of the glass dial and spaced therefrom a short distance is the activator member, which may be a radioactive foil or a film of coating composition containing a radioactive material. In either case, the activator member is non-luminous, but gives off alpha rays which strike the markers on the glass side or dial and cause the zinc sulphide therein to glow. The glow will continue as long as the alpha rays bombard

2

the zinc sulphide, but bombardment can be interrupted in accordance with my invention by interposing between the activator member and the face member, i. e. the glass plate bearing the markers, a sheet of material, for example, a metal slide which is impervious to alpha radiations. By interposing the metal slide between the glass slide and the radioactive film, except when the indicator is in use, the life of the face member can be increased many times.

In another form of the apparatus of my invention, which is herein claimed, the face member, constructed like an ordinary clock dial, is of translucent material, with one or more numbers or other markers painted on the face thereof with a non-luminous but ray-responsive phosphor, such as zinc sulphide paint. The activator member in this case is a pointer which rotates around in front of the markers, which conveniently are arranged in a circle with the axle of the pointer as a center. The pointer carries a radioactive foil or film on its underside in the neighborhood of the markers. As the pointer rotates, each marker on the dial is caused to glow consecutively while the others remain dark. This type of structure affords two distinct advantages. The life of the phosphorescent material, i. e. the zinc sulphide paint is increased because most of the time each marker is beyond the range of rays given off by the radioactive foil or film on the pointer member, and so does not deteriorate under bombardment. Moreover, the eyes of an observer are caused to concentrate on only the pertinent observation, i. e. the marker that is illuminated. This reduces fatigue, an important consideration in night flying and the like.

These and other features of my invention will be understood more thoroughly in the light of the following detailed description, taken in conjunction with the accompanying drawing, in which:

Figs. 1 and 2 illustrate one type of indicator mechanism constructed in accordance with my invention;

Figs. 3, 4, 5 and 6 illustrate modified and preferred forms of indicators of my invention; and

Fig. 7 illustrates a further form of apparatus of my invention in which the bombardment of the responsive phosphor is interrupted by interposing a screen such as a metal slide between the phosphor and the activator member where the rays originate.

Referring to Figs. 1 and 2, it will be observed that the apparatus comprises a face or dial member 10, provided with a plurality of markers 11,

12, 13, 14, 15, 16, 17, 18 on the face of the marker and arranged in a circle around its periphery. The markers are films of a non-radioactive phosphor, for example zinc sulphide paint, which contains no radioactive substance but which will glow under bombardment by alpha particles. The apparatus is also provided with a pointer 19 in the form of an ordinary clock hand rotatable about an axis 21 at the center of the dial. On the underside of the pointer near its outer end and immediately over the circle of markers is placed a radioactive member 22 such as a piece of radioactive foil or a radium film. The radioactive foil or film is spaced from the markers, but passes over them when the pointer is rotated, so that each marker successively is bombarded by alpha rays. The pointer is rotated by means, such as a clock-work (not shown). However, as it rotates, only that portion of the marker or markers which is being usefully employed for observation purposes is activated at the moment. The other markers are outside the range of the alpha particles and so are at rest and unbombarded.

The dial constructed in accordance with Figs. 1 and 2 will last many times longer than dials formed by painting the several markers with a self-luminous paint, for example, a paint formed of zinc sulphide containing a radium active substance, such as radium chloride.

Figs. 3, 4, 5 and 6 illustrate three preferred modifications of an indicator constructed in accordance with my invention. In all cases, the apparatus comprises a dial or face member 30 of transparent or translucent material, for example glass or plastic. The front face of the dial is masked with a material which cuts off light. Thus, the face of the material, except at the markers 31, 32, 33, 34, 35, 36, 37, 38, may be coated with black paint or the like. The marker areas, however, are transparent or translucent and the back of the dial, at least in the region of the translucent markers, is covered with the non-radioactive but responsive phosphor 44, for example zinc sulphide paint.

As shown in Figs. 4 and 6, the responsive phosphor 44 may be used to coat only the marker areas themselves or, in the case in which the front of the dial has been painted black except at the markers, the whole back surface of the dial may be painted with the responsive phosphor 45, as shown in Fig. 5.

In the case of the three types illustrated by Figs. 4, 5 and 6, the apparatus is provided with a pointer 40 which is mounted behind the dial and bears an activator 41 of radioactive material, for example, a piece of radioactive foil prepared as described and claimed in copending application Serial No. 407,098, filed August 15, 1941, by Alois Fischer. The foil is mounted on the tip of the pointer opposite the circle of markers.

As shown in Fig. 4, the pointer may be driven by a shaft 42 from inside the apparatus so that the front plate or dial has no openings in it, an advantage when dealing with radioactive substances. However, the pointer may be mounted on a shaft 43 which passes through the center of the dials as in Figs. 5 and 6. In all cases, the pointers are rotated by conventional means (not shown).

When the dials of Figs. 1 and 3 are viewed from the front in the normal manner, only the pertinent marker will be illuminated. Thus, for example, if the pointer is half way between the numerals 5 and 10 on the dial only a small bright

spot 50 will appear on the marker arc between the numerals 5 and 10.

Naturally enough, the markers on the dial may take a great variety of forms and may be placed in a variety of ways.

In the apparatus of Fig. 7, the activator member is not movable. In this apparatus, the face comprises a glass slide 70 on the underside of which a plurality of markers 71, 72 are provided. 10 These markers are made of non-radioactive but responsive phosphor such as zinc sulphide paint. The glass slide is mounted in a case 73 of conventional design. The bottom of the case 74 is coated with a film of radioactive substance, for example, a sheet of radioactive copper foil 75.

Alpha rays from the foil cause the markers on the underside of the glass slide to glow when the apparatus is in use. When the apparatus is taken out of service a removable metal slide 76 is slid 20 into the case between the foil and the phosphor, thereby blocking off alpha radiations and permitting the markers to "rest."

I claim:

1. In a self-luminous indicator, the combination which comprises a translucent face member, a marker mounted on the back of the face member and formed of a non-radioactive but responsive phosphor capable of being activated by alpha rays, a pointer spaced from but movable over the rear surface of the face member in proximity to the marker, and a radioactive member of non-luminescent radio-active material which emits alpha rays, said radioactive member being mounted on the pointer in such a position that alpha rays therefrom strike the marker when the pointer passes over it.

2. In a self-luminous indicator, the combination which comprises a translucent face member, a marker mounted on the back of the face member and formed of a non-radioactive but responsive phosphor capable of being activated by alpha rays, a mask mounted on the front of the face member to obscure the face except in the neighborhood of the marker, a pointer spaced from 40 but movable over the back surface of the face member in proximity to the marker, a radioactive member of non-luminescent radioactive material which emits alpha rays mounted on the pointer in such a position that alpha rays from the member strike the marker when the pointer passes over it.

3. In a self-luminous indicator, the combination which comprises a translucent face member, a unitary marker coating affixed on the back of the face member and formed of a non-radioactive but responsive phosphor capable of being activated by alpha rays, a mask on the front of the face member, said mask having openings therein arranged in an indicator pattern and adapted to permit observation of phosphorescence induced in the marker coating, a pointer spaced from but movable over the surface of the face member in proximity to the marker, and a radioactive activator member of non-luminescent radioactive material which emits alpha rays, the activator member being mounted on the pointer in such a position that alpha rays therefrom strike the marker coating when the pointer passes over it.

4. In a self-luminous indicator, the combination which comprises a translucent face member, a marker mounted on the back of the face member and formed of a non-radioactive but responsive phosphor capable of being activated by alpha rays, a movable member spaced from and

movable over the rear surface of the face member in proximity to the marker, and a radioactive portion of non-luminescent radioactive material which emits alpha rays, said radioactive portion being mounted on the movable member in such a position that alpha rays therefrom strike the marker when said portion passes over it.

5. In a self-luminous indicator, the combination which comprises a translucent face member, said face member being masked except for unmasked translucent portions constituting indication marks, an area of phosphorescent material

coating the back surface of the face member behind each unmasked portion, an activator member mounted adjacent said face member, said face and activator members being relatively movable, and a coating of radio-active material mounted and positioned on said activator member so that said movement causes said radioactive material to pass in activating proximity to said areas of phosphorescent material on the back of said unmasked portions.

CLARENCE W. WALLHAUSEN.
